UNITED STATES PATENT OFFICE.

DANIEL DRAWBAUGH, OF EBERLY'S MILL, ASSIGNOR TO G. MILTON BAIR, OF HANOVER, AND CALVIN W. REAM, OF READING, PENNSYLVANIA.

DOUBLE-DIAPHRAGM TELEPHONE-TRANSMITTER.

SPECIFICATION forming part of Letters Patent No. 552,469, dated December 31, 1895.

Application filed February 23, 1895. Serial No. 539,476. (No model.)

To all whom it may concern:

Be it known that I, DANIEL DRAWBAUGH, a citizen of the United States, residing at Eberly's Mill, in the county of Cumberland 5 and State of Pennsylvania, have invented certain new and useful Improvements in Double-Diaphragm Telephone-Transmitters; and I do hereby declare the following to be a full, clear, and exact description of the invention, such as will enable others skilled in the art to which it appertains to make and use the same.

This invention relates to telephone-transmitters.

15 The object is to produce a microphone-transmitter which shall have increased resonance and be ready of adaptation and convenient in use.

With this object in view, the invention resides, generally, in a microphone-transmitter in which two or more diaphragms, in whole or in part of conductive substance, constituting a double or multiple diaphragm, are arranged in a vocalizing-chamber, edgewise to 25 the mouthpiece thereof, a diaphragm at one side connecting with a battery and a diaphragm at the other connecting with the line.

Furthermore, the invention resides in the construction and details thereof, substantially as hereinafter described and as illustrated by examples in the drawings.

Referring to the drawings, in which two of many forms of embodiment of my invention appear, and in which like letters of reference indicate corresponding parts, Figure 1 is a view in central longitudinal horizontal section showing an arrangement of two diaphragms in a casing constituting the vocalizing-chamber, the diaphragms being wholly of 35 conductive substance separated by a disk of non-conductive substance having a central opening, the diaphragms having centrally within opposing fixed carbon buttons or electrodes between which is granular or powdered 40 carbon retained between the electrodes by a disk of sponge or other spongiform—that is, soft, porous, and elastic—substance, having a central opening for the buttons and set into and fitting in the central opening in the separating-disk, the vocalizing-chamber appearing 45 with its mouth-piece at one end and a vent

to the external air at the other, with which the space between the diaphragms communicates, and as pivoted in a bracket and an arm therefrom, showing, furthermore, one diaphragm connected with the wire from battery and external connection from the other diaphragm to line, the internal connection from this diaphragm at a part of the same farthest from the internal connection of the 55 first not appearing. Fig. 2 is a view in central transverse horizontal section showing the casing put together in two lateral parts, and an internal longitudinal circumferential groove in the casing to communicate with the 60 vent, and openings or channels in the separative disk from between the diaphragms into the groove, showing, also, the internal connection from the other diaphragm to the external connection to line. Fig. 3 is a view in 65 side elevation of the transmitter in different positions of use and in circuit by spring action and out of circuit by the weight of a receiver hung upon it, showing the casing with a central lateral disk for each side having a 70 portion insulated and provided with contacts for the external connections from battery and to line. Fig. 4 is a view in detail of the separating-disk, showing the same with the central opening holding the sponge having a central opening for the carbon buttons to enter 75 and to hold the granular carbon and showing perforations outside the central opening, and in dotted lines the situation of the channels from one side of the rim of the disk leading 80 to the other side, and, also in dotted lines, another situation in which the channels may be located—namely, from the perforations outward through the circumference. Fig. 5 is another view in central longitudinal horizontal section showing the diaphragms partly 85 of non-conductive and partly of conductive substance and without the separating-disk, the diaphragms being formed each of such a part as would result from taking a disk like 90 that shown in Fig. 4, but with a smaller central opening splitting it in two edgewise and turning the faces inward and covering the central opening with metallic plates, showing, furthermore, connection from the battery- 95 wire to the conductive part of one diaphragm by a radial metallic strip thereon, and show- 100

ing the position of the sponge. Fig. 6 is another view in central transverse horizontal section, and of the device of Fig. 5, showing beyond what is therein displayed, the radial 5 strip from the metallic portion of the other diaphragm to internal and external contact to line; and Fig. 7 is a view in side elevation of one of the diaphragms made partly of non-conductive and partly of conductive sub-10 stance, showing the radial contact-strip.

Referring to the drawings, A indicates a casing constituting a vocalizing-chamber, the same comprising two parts a and a^2 , suitably held together, as by providing one of the 15 parts with a circular mortise a^3 , adapted to be engaged by a circular tenon a^4 arranged on the other part. The chamber is constructed of any suitable material, preferably of hard rubber, and is provided at one end with a 20 threaded portion a^5 , onto which to screw the mouthpiece a^6 . Arranged longitudinally and centrally of the chamber and clamped in suitable recesses a^7 therein are two or more diaphragms B and B^2 , constructed of any suitable 25 material, and held at a suitable distance apart by means of an insulating and separating disk C. Each of the diaphragms carries a carbon button b and b^2 , respectively, which project into a circular orifice of an annulus D interposed between the diaphragms and held in 30 place within a circular orifice c of the disk C, a body of granular carbon E being interposed between the buttons for the purpose of preventing make and break of the circuit. The 35 annulus D is constructed of a suitable spongi-form material—such as sponge, sponge-rubber, or any other suitable porous, non-conductive material. The casing is provided with an interior circumferential channel a^8 , 40 which connects with the external atmosphere by means of an orifice a^9 . The disk C is provided with a series of openings c^2 , opening into the channel a^8 , by means of which atmospheric air is admitted to the vocalizing-chamber in 45 order to equalize the temperature therein. As shown in Fig. 2, the openings c^2 are arranged obliquely to the face of the disk C, but, if desired, the disk may be provided with a series of openings c^3 surrounding the annulus, and 50 from these openings lateral orifices c^4 project to the periphery of the disk, as indicated by dotted lines in Fig. 4. As shown in Figs. 1 and 2, the diaphragms are made wholly of conductive material.

55 The sides of the casing are provided with trunnions or bearings F, one of which engages a suitable support on the wall or the like, and the other a bracket G, the trunnions being insulated from their supports by means 60 of suitable insulators f. The sides of the casing are further provided with contact-plates H, whereof a section of each, h , is insulated and provided with a contact-point h^2 , one on each side of the casing, the said points being 65 engaged by spring-contact arms I. When the arms are on the contact-points, the call-circuit is cut in, but as soon as the telephone-

receiver J is detached from the transmitter a spring K draws the transmitter to the position shown in full lines in Fig. 3, in which 70 position the contact-arms are on the uninsulated portion of the contact-plates H, thus cutting the talking-circuit in. As will be seen by reference to Fig. 3, the insulated portion h is of comparatively small size, so that 75 the transmitter may be used at any point from a plane slightly below a horizontal line to an approximately vertical position, thereby 80 accommodating it to persons of different statures.

In Figs. 5 and 6 the same construction of casing is shown as that illustrated in Figs. 1 and 2, and the same means are employed for conducting the current to the diaphragm—namely, spring-contact points I and I^2 —which 85 contact, respectively, with contact-points i and i^2 , connecting through the medium of conducting-plates i^3 and i^4 with the diaphragms. The difference of arrangement in 90 the latter figures is in the diaphragms, such difference consisting in the dispensing with the metallic diaphragms of a size practically equivalent to the internal diameter of the vocalizing-chamber and employing in lieu thereof metallic strips M, to which are attached the carbon buttons m. Instead of 95 having the disk C interposed between the diaphragms the same is constructed in two parts, as clearly shown in Figs. 5 and 6, between which the annulus D is held. In operation 100 this particular form of diaphragm will be found to operate as successfully as that form shown in the first two figures, and from a standpoint of simplicity and economy may 105 in some instances be employed to advantage.

In order to prevent the heat from the breath of the person using the telephone from interfering with the adjustment of the diaphragm, a shield N is provided at the point of the diaphragm opposite the mouthpiece.

The advantage claimed for this particular construction of telephone and the employment of double diaphragms is that increased resonance is effected, together with capability of greater vibration of the diaphragms, thereby peculiarly fitting this particular form of telephone for effective service in exchange work. The shield N also subserves the further function of dividing the sound so as to cause it to act equally upon both diaphragms 120 to produce equal and synchronous action thereof.

Having thus described my invention, what I claim, and desire to secure by Letters Patent, is—

1. In a microphone-transmitter in which two or more diaphragms constituting a double or multiple diaphragm are arranged in a vocalizing chamber, the combination with the diaphragms carrying carbon buttons, of an interposed insulating disk, a spongi-form annulus in which the buttons fit, and a body of granular carbon between the buttons, substantially as described.

2. The combination with a multiple diaphragm transmitter, of an insulating disk separating the diaphragms, a flat elastic or spongiform annulus fitting within an opening in the disk and filling the space between the diaphragms, carbon buttons carried by the diaphragms and fitting in an opening in the annulus, and a body of granular carbon interposed between the buttons, substantially as described.
3. A two - part vocalizing chamber, diaphragms clamped at their edges between the sections thereof, an insulating and separating disk interposed between and contacting near its periphery with the diaphragms and held
- in place thereby, a flat spongiform annulus interposed between and filling the space separating the diaphragms, and engaging an opening in the disk, carbon buttons secured directly to the diaphragms and projecting into an opening in the annulus, and a body of granular carbon interposed between the buttons, substantially as described.
- In testimony whereof I affix my signature in presence of witnesses.
